UNITED STATES PATENT OFFICE.

JAMES I. METTLER, OF CRESTON, ILL., ASSIGNOR OF ONE-HALF, BY MESNE ASSIGNMENTS, TO CHARLES WOODWARD, OF SAME PLACE.

ATTACHMENT FOR HOLDING SICKLE-BARS WHILE BEING GROUNDED.

SPECIFICATION forming part of Letters Patent No. 340,346, dated April 20, 1886.

Application filed March 13, 1885. Serial No. 152,707. (No model.)

To all whom it may concern:

Be it known that I, JAMES I. METTLER, a citizen of the United States of America, residing at Creston, in the county of Ogle and State of Illinois, have invented certain Improvements in Attachments to Grindstones for Holding Sickle-Bars, Mowing-Machine Knives, Scythes, &c., while being Ground; and I do hereby declare the following to be a full, clear, and exact description of the invention, such as will enable others skilled in the art to which it appertains to make and use the same.

This invention relates to an adjustable frame for use in connection with grindstones for holding the sickle-bar of a mowing-machine or other long-bladed knife while being sharpened, the object being to hold the knife steady against the face of the grindstone at a predetermined angle, whereby its several parts or saw-teeth are evenly and completely sharpened at corresponding bevels, the edge of a saw-toothed knife, scythe, or other long-bladed cutter being by my improvements held at the same pitch or angle to the face of the grindstone, in order that every tooth or part thereof shall be ground down to the same bevel.

Although I have represented the device as operating upon a sickle-bar, the invention is equally well adapted for use in the grinding of scythes and other knife-edges.

In the accompanying drawings, Figure 1 represents a perspective view of my improvements applied to a grindstone-frame. Fig. 2 represents a vertical elevation, partly in section, the section being taken through the line *a b* of Fig. 1, to show the manner in which the knives are held in position against the grindstone. Fig. 3 is a detail view showing a metal tie-plate, for strengthening the frame of the grindstone.

A represents the grindstone-supporting frame; *B*, the grindstone; *C C*, the double foot-treadles; and *D*, an adjustable seat for the operative, said seat being secured in position by a bolt, *b⁴*, having bearing in a cross-bar, *a³*, on the under side of the framing.

D' represents the table, upon which the adjustable sickle-bar frame, to be presently described, is supported.

a represents a longitudinal slot formed in the table *D'*.

a' represents a curved metallic base-plate, which is secured to the slotted table, with capability of easy and rapid circular movement, and also longitudinal adjustment thereon, and toward and from the grindstone by a bolt, *b*, having a suitable securing-nut. 55

b' represents upwardly-extending ears, formed on the respective ends of the curved base-plate *a'*. These ears are provided with holes *b²*, through which is passed a bent rod, *b³*, having upwardly-extending arms having loop ends *c*.

c' represents a straight rod passed between the upper looped ends of the bent rod *b³* and 65 connecting the same, the respective ends of said rod *c'* extending a short distance beyond the outer faces of the arms of the rod *b³*, to receive two bracket-arms, *d d*, one of which is loosely held upon each of said projecting ends 70 of the rod *c'* by nuts *c²* on the ends of said rod *c'*.

c² represents stop-nuts on the rod *c'*, within and bearing against the inner faces of the upright arms of the bent rod *b³*. 75

d represents holes formed in the bracket-arms *d*, to receive and loosely hold the sickle-holding bar *d²*.

d² represents rests formed on or near the ends of the sickle-holding bar *d²*, for the double 80 purpose of affording means whereby said bar may rest upon the frame or other suitable support, and also of affording rests or supports for the ends of the sickle or knife while being operated upon. 85

d⁴ represents a central stop or clamping-plate extending transversely from the upper face of the sickle-holding bar, for the purpose of holding the knives in position and preventing their upward movement while being 90 ground.

E represents the tongs, by means of which the sickle under treatment is clamped and held in position. Of these two pairs are employed. 95

e e' represent the handles, the lower member, *e'*, of which has at its jaw or gripping end a hole, *e²*, within and through which the bent or curved jaw end *e²* of the upper member, *e*, is passed and locked. By this construction and manner of connecting the jaw ends of the two arms of the tongs a hinge- 100

connection is formed at their jaw ends, by means of which the handles may be turned aside to permit of the insertion between them of the sickle *f*. When the sickle has been placed in position, the bent arm or handle *e* is turned around to a position above the lower arm or handle, thereby bringing the rearwardly-curved portion of the handle *e* into clamping contact with the sickle, and thereby securely holding said sickle rigidly in position upon the holding-bar *d*². The straight connecting-rod *c*' serves as a support and guide for the lower handles of the tongs to rest upon, enabling each section of the knife to be ground to the same predetermined bevel. Without the guide and supporting rod *c*' it is obvious that the same bevel could not be preserved throughout the length of the knife, as were such guide-rod absent the operative would naturally feed the knife in an irregular manner.

In order to strengthen the frame supporting the grindstone a metal tie-plate (shown in detail in Fig.3,) is used. This is constructed as follows: *g*, *g*' represent metal tie-plates, and *g*² a cross-bar interposed between the ends of the frame-bars *A*. The ends of the frame-bars *A* and the cross bar are clamped together by a bolt, *h*, passed therethrough. The tie-plates *g* have flanged sides which lap over the ends of the cross-bar *g*², the tie-plates *g*' having similar side flanges, *h*', which overlap the sides of the bars *A* at right angles to the flanges of plates *g*, as clearly represented in the drawings. These flanged plates may have their flanges attached to the bars *A* and *g*² by screws and bolts, if desired. By this construction and arrangement the ends of the grindstone-supporting frame are effectively braced and strengthened, whereby they are rendered very strong, and will not be injuriously affected by very rough usage or heavy work.

In order to adjust the sickle or knife and its holding device to the proper position the curved base plate *a*' is loosened in its support, the sickle-bar or knife is then placed in the appropriate position upon the holding-bar *d*², to bring the teeth or edge thereof at the desired angle to the grindstone at which they are to be ground, said bar *d*², bent rod *b*³, and base-plate *a*' being correspondingly turned or slid either backward or forward, as the case may be, whereupon upon the desired position of the article to be ground being thus secured relatively to the grindstone the nut on the

bolt *b* is tightened upon the base-plate, thereby securely clamping the same and securing the knife-holding frame in the appropriate position for securing the regular grinding of the knife, scythe, or other article to be ground. 60

The operator while grinding may at any time obtain a view of the under edge of the knife being sharpened by simply bearing backward upon the tongs, using the guide-bar *c*' as a fulcrum, by which act the sickle-holding bar *d*², bracket-arms *d*, and sickle or knife will be rocked or swung rearwardly and upwardly, so as to bring the under side of the knife to view.

To effect a sufficient adjustment of the knife-holding frame it will sometimes be necessary (such, for instance, as when the knife to be sharpened is of considerable width,) to move the seat as well as the base-plate.

Having thus described my invention, what I claim is--

1. In combination with a grindstone frame, the adjustable seat and table and the adjustable sickle-bar frame having at its upper portion a tong-supporting and guiding bar, substantially as described. 80

2. The combination, with a grindstone-frame, of a slotted table or support, a curved base-plate adjustably connected to said slotted table and having upwardly extending ears, an upwardly-extending bent bar supported within the eared base-plate, and having at its upper portion a connecting and tong supporting and guide bar and bracket-arms, a sickle-holding bar supported within said bracket-arms, and tongs for gripping the sickle or knife, substantially as set forth. 90

3. A sickle bar frame consisting of an adjustable base-plate, upright rod or rods held at their lower part in the base-plate and at their upper ends by a horizontal guide and supporting rod, said horizontal rod supporting and guiding the tongs and sickle-bar support in their transverse movements, the bracket-arms and sickle-bar holder, and the tongs for holding the sickle bar in position, constructed and operated substantially as described. 95

In testimony whereof I affix my signature in presence of two witnesses.

JAMES I. METTLER.
